UNITED STATES PATENT OFFICE

120,944

DESIGN FOR A DRESS ENSEMBLE

Jacob H. Alkon, New York, N. Y.

Application May 1, 1940, Serial No. 92,058

Term of patent 3½ years

To all whom it may concern:

Be it known that I, Jacob H. Alkon, a citizen of the United States of America, residing in New York city, in the Borough of Manhattan, county and State of New York, have invented a new, original, and ornamental Design for a Dress Ensemble, of which the following is a specification, reference being had to the accompanying drawing, forming part thereof, wherein,

The characteristic feature of my design resides in the combination on the ensemble disclosed of the specific dress member which is striped and pleated as shown.

I claim:

The ornamental design for a dress ensemble, substantially as shown and described.

JACOB H. ALKON.
